UNITARY MOTOR-PUMP ASSEMBLY

Russell T. Smith and Frederic L. Tarleton,
Greenville, Mich., assignor to Gibson Electric
Refrigerator Corporation, Greenville, Mich., a
corporation of Michigan

Application May 20, 1933, Serial No. 671,984

1 Claim. (Cl. 230—58)

This invention relates to pumps, compressors and the like, and driving means therefor, and more particularly to an improved motor-compressor unit so constructed that it may be hermetically sealed, and adapted especially for use in refrigerating systems.

An important object of the invention is the incorporation in such an hermetically sealed motor-compressor unit of improved means for lubricating the working parts, for controlling and guiding the flow of oil or other lubricant, and for maintaining the lubricant in and returning it to a desired portion of the housing or enclosure.

A further object is the provision of improved means for supporting and journaling the moving parts.

Still another object is the provision of an improved casing construction for such a unitary motor-compressor.

Still further objects will readily occur to those skilled in the art upon reference to the following description and the accompanying drawings in which

Figure 1 is a vertical longitudinal section taken substantially thru a motor compressor unit incorporating the principles of this invention.

Figure 2 is a section taken substantially on the line 2—2 of Figure 1 and looking in the direction of the arrows;

Figure 3 is an elevation of the right end of the unit shown in Figures 1 and 2.

Figure 4 is a vertical section taken substantially on the line 4—4 of Figure 1 and looking in the direction of the arrows.

Figure 5 is a schematic diagram of the motor connections.

Referring now to the drawings, reference characters 10 and 11 designate the two main sections of a casing which houses the entire unit. The section 10 may be termed the motor casing section, and the part 11 the compressor casing section, since the indicated portions of the housed apparatus are principally contained in the sections stated. The two casing sections are substantially cylindrical and provided with threadedly interfitting portions (12) enabling their being screwed together to form a single housing, as shown in Figures 1 and 2. The threads may be tapered, and solder may be applied to the joint as well, as at 14, to insure hermetic sealing.

Axially thru the substantially cylindrical housing so formed extends a fixed shaft 16 supported at one end by a boss 17 cast in casing section 10 and at the other by a support integral with the

casing section 11, the bore in which the shaft is fixed at this end communicating with a trough-like oil channel 20 to which oil is delivered when the machine is in operation, in a manner presently to be described. Shaft 16 is axially drilled as at 18 to provide an oil channel which communicates with the trough 20, into which the end of the shaft projects, so that oil is conducted through the entire length of the shaft.

Journalled on the fixed shaft 16 is a hollow 10 shaft 21, carrying at one end and within the motor casing section the rotor 22 of an electric motor, shown as of the squirrel cage induction type. As shown in Figure 5, the motor is connected for condenser starting in a manner which 15 eliminates from the housing all sparking contacts and all moving electrical parts except the rotor. The windings of the motor comprise a running winding 75, a starting winding 76, and a control winding 77. The control winding is energized 20 only by counter electromotive force. In a series with the starting winding is a condenser 78 of 25 relatively large capacity. The 115 microfarad size indicated seems correct for a motor of about one-fifth horse power. The switch 79 which 30 controls the current to the starting winding is actuated by and forms part of a differential relay, one winding (80) of which tends to close the switch and is in series with the supply to the main or running winding. When the switch 81 35 is closed, relay winding 80 is energized and switch 79 thereby closed. This energizes the starting winding 76, the current in which leads the voltage by reason of the presence of condensers 78, while this split-phase effect starts the motor 40 reliably on single phase supply in a manner which will be readily understood.

It will be appreciated that the current induced in the auxiliary control winding 77 will 40 be at a minimum when the motor is first started but builds up with the counter electromotive force as the current drops off in windings 75—76. At the start the current in relay winding 82, which tends when energized to open switch 79, will also 45 be light. As the motor gathers speed the counter electromotive force builds up; the current in windings 75, 76, and 80 falls away, and concurrently increases in winding 77 and so in relay solenoid 82, which when fully energized overcomes the force exerted by the now weaker solenoid 80, 50 thereby opening the switch 79 and cutting out the starting winding 76.

The motor terminals 85 extend through the end of the casing, as best shown in Figs. 1 and 2, 55 and a fan motor 87 carried by and upon the out-

side of the same end of the casing is supported by a plate 88 which also serves as a terminal cover. The same terminals may be used for making connections to the fan motor, the shaft 89 of which is adapted to carry a cooling fan (not shown).

The construction of the compressor generally follows that disclosed in the patent to Russell T. and Charles H. Smith, No. 1,890,238, issued December 6, 1932. Upon its end within the compressor casing section the hollow shaft carries an eccentric 30 encircled by a strap 31', which is formed as an integral end of a connecting rod 31 coupled as by means of a wrist pin 32 to a double piston unit comprising opposed outwardly facing pistons 33—34 rigidly connected as by means of a rib 35 integral with both, and slotted as at 36 to clear the shaft 16. The opposed cylinders 37—38 in which the pistons may travel may be formed integrally with casing section 11. Suitable cylinder heads as 40—41 are secured as by means of cap screws 42 over the open ends of the cylinders, and carried by the heads are outlet flap valves 43—44 caged in enlarged bores in the heads and held seated against the valve orifices (undesignated) in valve plates 45—46 by means of compression springs 47—48. The outlets are connected as by means of channels 49—50—51 to a bore 52 opening in the end of casing 11 and in which the outlet coupling 53 is tightly secured as shown in Figures 1 and 3.

The inlet ports 55—56 opening in the side walls of the cylinders are arranged to be uncovered by the pistons as the latter approach the bottoms of their strokes to admit a charge in the well known manner. Ports 55—56 are connected by means of a channel 57 formed in casing section 11, to which channel the inlet pipe 58 is connected. The inlet pipe opens directly into the interior of casing 11, its upstanding open end being angled in a manner adapted to prevent the splashing of oil thereinto, as will subsequently become apparent, and the inlet to the unit as a whole is directly thru the wall of casing section 11, an inlet coupling 54 being shown attached to and over an inlet opening (not shown) in the wall (Fig. 3).

The bottom of casing section 11 forms an oil pan which may be drained by means of plug 59 and into which dips an oil splash 60 formed integrally with and projecting downwardly from the connecting rod strap 31'.

Also carried by the shaft 21 is a counterbalance weight 62. An oiling disc 61, rotatable with the shaft is mounted thereupon adjacent the counterweight and fastened to the latter, as shown in Figure 2. The disc 61 also dips into the oil in the bottom of the casing and during operation of the compressor serves to throw against the walls by centrifugal force the oil it picks up. A certain amount of such oil is thrown into a channel 19 cast integrally upon the side wall of casing 11 as best shown in Figure 4. The channel 19 is inclined downwardly toward and communicates with the transversely extending trough 20, so that oil thrown into channel 19 by the disc 61 is conducted to trough 20, whence by reason of the previously mentioned communication between channel 20 and the bore 18 in the fixed central shaft, by reason of the intersection of the shaft-supporting aperture and the trough, the oil is led to bore 18 and flows along the entire length of the fixed shaft therethrough. At desired points along the fixed shaft radially extending passages, as 18', are formed extending

through its walls and connecting the central oil channel 18 with the bearing surfaces of shafts 16 and 21. Spirally cut exterior oil grooves may be formed upon the bearing surface of shaft 16 and communicating radial and spiral grooves are arranged at both the compressor and motor ends of journaled shaft 21. Escape channels 23 extend through the wall of shaft 21 between the rotor 22 and boss 17, opening into the interior of casing section 10, and with these one or more of the radial channels 18' may communicate. Through apertures 23 oil in properly limited quantities may escape into the interior of the motor casing section, being also forced thereinto and flow through the central channel assisted by centrifugal force when the motor is running. The windings and other parts of the motor of course warm up when the motor is running, and the oil in this casing section is accordingly warmed by contact therewith.

A partition 65 separates the motor and compressor sections of the casing, and undesired leakage of oil from the compressor to the motor section along the surface of shaft 21, or through the space between such shaft and the aperture 25 in partition 65 through which it extends, is prevented by a sleeve-like sealing ring 66 frictionally held against the partition at its one end and against the rotor 22 at the other, such friction being supplied by a compression spring 67 trapped between the motor end of tubular shaft 21 and the head of casing section 10, and positioned, as best shown in Figure 2, by the boss 17. It will be seen that the spring imposes end thrust upon the shaft urging it to the right as viewed in the drawings.

As above stated, the escape of a certain amount of oil in the motor section of the casing is provided for, in order that the motor may perform the valuable function of warming the oil. Preferably, however, means are provided for preventing the oil level in this casing section from rising to such height that oil occupies the gap between the rotor and stator of the motor, and for returning the excess oil to casing section 11. For this purpose a channel 70 (Figure 1) extends through partition 65, opening at its lower end upon the motor side and closer to the floor of the casing than the bottom of such annular gap. At its upper end the channel 70 opens upon the compressor side near shaft 21. Since the compressor inlet opens, as above stated, directly in casing section 11, the pressure is reduced in such section as soon as the compressor is started, and any oil in casing section 10 above the mouth of channel 70 is accordingly quickly drawn through such channel into the compressor section of the casing whenever the unit is started, since the only other passage connecting the casing sections (that through the oil bore 18 and connected channels) is relatively very restricted. A circulation will be seen to be so maintained, oil being constantly delivered to the casing section 10 through apertures 23 when the unit is running and withdrawn thru passage 70.

By reason of the unitary enclosure of both compressor and motor in a common housing, and the provision of a common lubricant circulation system, in the manner disclosed, the unit when used in a refrigerating system may be provided with a generous supply of oil without danger of harmful effects resulting from interaction of the oil and refrigerant at low temperatures. There is no necessity, as in other arrangements, of pro-

viding a special heater to prevent the oil from being cooled by the refrigerant to an undesirably low temperature, as the heat generated by the motor is sufficient for the purpose. The current saving thus effected is considerable, as even a small heater is wasteful of current.

Now having described the invention and the preferred embodiment thereof, it is to be understood that said invention is to be limited, not to the specific details herein set forth, but only by the scope of the claim which follows.

What we claim is:

In an enclosed motor-compressor unit, a casing, a partition therewithin dividing the casing into separate sections, a motor within one of said sections and including a portion which generates heat when the motor is running, a compressor within another section, a common shaft assembly extending into both such sections and supporting parts of both the motor and compressor, said shaft having a longitudinal oil channel therein, and also having an inlet communicating with said oil channel within the compressor section,

and an outwardly extending outlet formed in a rotatable portion of the shaft within the motor section and terminating in an exposed surface of the shaft, the compressor section having an oil reservoir therein, means for feeding oil from said reservoir to the channel inlet, whereby upon rotation of the shaft portion having said outlets therein centrifugal force tends to draw oil through the channel from the inlet and discharge it into the motor section, the compressor having an inlet opening into the section in which it is housed, and the partition having an opening therethrough connecting said sections and opening in the motor section at a height allowing the maintenance of a desired quantity of oil in the motor section to be heated by said portion which generates heat, whereby the compressor tends to draw all oil above the level of the inlet opening into the section in which it is housed by reducing the pressure therein. 20
